UNITED STATES PATENT OFFICE.

FRANK H. STETSON, OF MELTUEEN, MASSACHUSETTS; ASSIGNEE TO U. S. BOBBIN & SHUTTLE CO., OF PROVIDENCE, RHODE ISLAND, A CORPORATION OF RHODE ISLAND.

SHUTTLE BLOCK.

Application filed December 1, 1922. Serial No. 604,280.

This invention relates to shuttles of the type wherein a metal threading block is inserted and fastened in a wooden shuttle.

With automatic or self threading shuttles, such blocks generally have a sloping or curved guiding front edge which extends backwardly along and in cooperation with a yarn passage which connects with the eye in the side, and as now made this front edge terminates in a downwardly projecting tongue which, together with a diagonal sloping back edge, engages the wood of the shuttle.

It is highly important that the joint between the metal and the wood, especially at the side corner, should be tight because as the yarn slips down it is under tension and if there is even a slight crack or space the yarn catches therein and breaks. Occasionally, it may slip up after being threaded and catch in the same way.

Broadly, this invention consists of a tooth positioned at the under outer edge at the point of contact between the wood and the metal which can be forced into the wood when the block is put in place whereby the yarn cannot catch if the joint is originally not tight, nor even if the wood afterwards shrinks away from the metal.

In the drawings, Figure 1 is a plan view of the front or eye end of an automatic shuttle with a threading block in position.

Fig. 2 is a side elevation of a similar shuttle with the threading block raised a short distance to show the relation of the parts.

Fig. 3 is a detail from below, and in front from the direction of the arrow in Fig. 2, of the tongue and tooth.

Fig. 4 is a detail from the bottom showing the tooth.

Fig. 5 is a view similar to Fig. 2 with the threading block forced into place and locked or fastened in position.

Fig. 6 is a view similar to Fig. 3 showing the tooth and the depression which it makes in the wood.

Fig. 7 is a detail view similar to Fig. 5 showing a tongue and tooth where the tongue projects slightly over the wood.

In the drawings, A represents a wooden shuttle with a tip 4 having an eye H in the side with the usual pins 17, 17 and a yarn passage extending between 16 and 19 to the threading chamber 12. This threading

chamber extends back to and connects with the bobbin chamber 1 which is cut out to receive the bobbin B from which the yarn C is unwound. There is also a recess indicated by E to receive the threading block F. This threading block extends forward at 39 to a hook or point and has the usual horn D at the forward end which extends down forwardly of the yarn passage from 16, 19 to 12, and has a guiding top front edge 32 which extends backwardly along and in cooperation with said yarn passage. This front edge 32 extends downwardly to a bottom straight front edge 30 and terminates in a downwardly projecting tongue 34 which forms a point at the back of front edge 32, the end of bottom edge 30, and the front of back edge 33 of a wing 31 which curves outwardly and downwardly, corresponding with the curve of the wood of the shuttle.

The wood of the shuttle back of the wall 16 of the yarn passage slopes back at 14 in such a way as to fit the back edge 33 which is straight at 10 to fit the bottom edge 30 of block D and at 15 comes to substantially a point, coinciding with the point of tongue 34.

It is in this place that the yarn is likely to catch, and to prevent catching I provide at the bottom of the outer forward end of the tongue 34 a tooth K which, as shown clearly in Figs. 2 and 5 and 3 and 6, when the threading block F is forced into position, makes its own depression or groove L in the wood. The block is locked in place by means of a screw, such as S, which passes through a hole 7 in the shuttle and through the threading block.

It is obvious that the depression or groove L might be made to fit tooth K before the block D is put in place, but this is unnecessary.

Being preferably of V shape, even if the wood shrinks away from the block D, the yarn is blocked from getting caught between them.

Even if, as shown in Fig. 7, the tongue 34 projects slightly beyond the junction point 15 and the back edge 16 of the yarn passage, the yarn cannot catch in slipping down and will not catch even if it slips up.

I claim:

1. The combination with a wooden shuttle having an eye in the side and a yarn passage extending therefrom to a threading chamber, of a threading block which has a horn at the

forward end which extends down forwardly of said yarn passage and has a guiding front edge extending backwardly along and in cooperation with said yarn passage and terminating in a downwardly projecting tongue which engages the wood of the shuttle, said tongue having at the bottom of the outer forward end a tooth which projects down and back and is forced into the wood.

2. The combination with a wooden shuttle, ¹⁰ of a threading block which has a guiding front edge which terminates in a downwardly projecting tongue which engages the wood of the shuttle, said tongue having a tooth which projects down and back at the ¹⁵ bottom, and is forced into the wood.

FRANK H. STETSON.
